UNITED STATES PATENT OFFICE.

ALBERT HAYES, OF NEW YORK, N. Y., ASSIGNOR, BY MESNE ASSIGNMENTS, TO
GEORGE F. MCKAY, OF NEW YORK, N. Y.

METHOD OF FORMING AND IGNITING EXPLOSIVE CHARGES IN INTERNAL-COMBUSTION ENGINES.

1,360,743.

specification of Letters Patent. Patented Nov. 30, 1919.

Application filed February 5, 1920. Serial No. 356,561.

To all whom it may concern:

Be it known that I, ALBERT HAYES, a citizen of the United States, residing at New York, in the county of New York, State of New York, have invented certain new and useful Improvements in Methods of Forming and Igniting Explosive Charges in Internal-Combustion Engines, of which the following is a description, reference being had to the accompanying drawings, forming a part hereof.

My invention relates to a method of operating internal combustion engines and particularly to a method of forming and igniting an explosive charge for such engines.

My invention has for its primary object to provide a method by which an effective explosive charge may be formed from heavy oil by mixing such oil with air compressed in the combustion chamber or cylinder of the engine and may be ignited without the use of special heating or igniting means. A further object of my invention is to provide a method of forming and igniting an initial explosive charge having heavy oil for its base without the use of light hydrocarbon for priming and without the use of special heating or igniting means, in other words to provide a method of forming and igniting an explosive charge by the use of which a heavy oil internal combustion engine may not only be operated without the use of any hydrocarbon other than the heavy oil and without special heating or igniting means but may also be started into operation without such use of hydrocarbon other than the heavy oil and without the use of special heating or igniting means.

Heavy oil internal combustion engines in which, after the engine has been heated up, kerosene and even fuel oil can be used as the basis of the explosive charge with more or less satisfactory results are known and used, but all such engines, so far as I am aware, require for starting their operation the use of light hydrocarbon to give the initial explosion or explosions or special means, such as electric coils or other special heating means for heating the heavy oil preliminary to the formation of the initial explosive charge and, usually, special means such as spark plugs, flame or incandescent igniting devices, for igniting the initial charge or excessively high compression by which a de-

gree of heat is produced equal to the temperature at which ignition takes place as in the Diesel type of engine.

By the use of the method of my present invention it is necessary in starting a heavy oil engine only to supply the heavy oil and a small amount of water and to cause sufficient movement of the engine piston to compress the air in the cylinder to a relatively low degree compared with the degree required in the Diesel engine.

With the above described objects and other objects hereinafter explained in view, my invention consists in the method of forming and igniting an explosive charge herein-after described and claimed.

Referring to the drawings which are to be understood as illustrative only and not as restricting the invention to the use of the apparatus shown or to the use of any particular apparatus, Figure 1 is a longitudinal central sectional view of part of the cylinder of an internal combustion engine equipped with a charge forming and igniting apparatus adapted to carry out my invention, and Fig. 2 is a detail view of the valve rod of such apparatus.

In the drawings 1 indicates the cylinder of an internal combustion engine here shown as horizontally arranged though it may be vertically arranged if desired, preferably provided with the usual water jacket 2. 3 indicates the engine piston. 4 indicates an opening through the wall of the cylinder and water jacket such as is usually provided to receive a spark plug, having its outer end enlarged and screwthreaded as shown.

In this opening 4 is arranged the charge forming and igniting device for carrying out my invention and by which the heavy oil used is heated and from which it is discharged in finely divided or gaseous form into the combustion chamber or cylinder to mix with the air compressed therein and form therewith an explosive or burning charge which is instantly ignited. This charge forming and igniting device comprises an outer screwthreaded portion 5 fitting the enlarged outer end of the opening 4, and an inner portion 6 extending inward to or nearly to the interior wall of the cylinder. Centrally through the inner and outer portions 5 and 6 is formed a charge cham-

ber 7 here shown as a cylindrical bore, having at its inner end a valve seat 8 for a valve 9 carried by a valve rod 10 which extends outward beyond the outer end of the portion 5 passing through and fitting closely in a central opening in a plug 11 which is screwthreaded into the outer end of the chamber 7. The plug 11 is provided on one side with an inlet passage 12 for oil leading to the charge chamber 7 and on its other side with an inlet passage 13 for water leading to the central opening through which the valve rod 10 passes. In the valve rod at a point which, when the valve is in closed position, is in line with the inlet passage 13 is formed a recess or pocket 14 adapted to contain a small quantity of water. A spring 15 carried by the outer end of the valve rod and bearing against the outer end of the plug 11 serves to keep the valve 9 against its seat and thus to keep the charge chamber closed except when the valve rod is actuated as hereinafter described.

25 An oil supply pipe 16 is connected with the oil inlet passage 12 leading from a suitable pump by which the charge chamber is intermittently supplied with oil, and a pipe 17 leading from a suitable water supply, preferably under constant pressure of gravity or otherwise, is connected to the water inlet passage 13.

The lower portion, or inner portion, of the charge forming and igniting device comprises a helical rib 18 having its outer diameter loosely fitting the opening in the wall of the cylinder, the helices being spaced apart a sufficient distance to leave between them a relatively wide space forming a helical chamber 19. The rib 18 is of relatively thick metal so as to retain the heat imparted to it while the walls 20 of the charge chamber between the helices of the helical rib are of relatively thin metal so as to transmit the heat of the hot gases to the contents of the charge chamber quickly. A cup shaped disk 21 of perforated metal incloses the inner end of the portion 6 being spaced a sufficient distance from the inner end of the charge chamber to permit the valve 9 to open freely.

In operation, when the engine is hot the explosion of a charge forces a portion of the incompletely burned gases through the perforations in the cup shaped disk 21 and into the helical chamber 19 heating the walls of the charge chamber and continuing to burn, keeping up the heat and probably maintaining sufficient flame to ignite the following charge. Oil is forced into the charge chamber from the oil supply pipe 16 and, at once, becomes highly heated but is held from ignition by the valve 9 which is held against its seat by the spring 15. On the compression stroke of the piston 3, as it reaches or nearly reaches the limit of its stroke, the upper end

of the valve rod 10 is struck by a suitably operated tappet or other operating means and is forced downward carrying the water downward to a point below the lower edge of the plug into contact with the hot oil, and at 70 the same time opening the valve 9. The water coming in contact with the oil which is heated to a high temperature, probably to not less than 400 degrees C, instantly causes an explosive effect and forcibly expels the 75 oil mixing with it and scattering it throughout the air compressed in the combustion chamber or cylinder forming a highly satisfactory and effective explosive mixture which is instantly fired. The flame from the 80 portion of the previous charge which is retained in and continues to burn in the helical chamber 19 serves as the igniting means though it is probable that the friction of the particles of oil passing rapidly through the 85 hot compressed air into which they are forced by the explosive force of the steam generated as above described produces an increase of temperature sufficient to cause ignition without the flame from the helical 90 chamber. This operation continues as long as the oil and water is supplied to the charge chamber. The explosive mixture thus formed from heavy oil, even from the heaviest low grade oil which is sufficiently 95 fluid to be fed to the charge chamber burns cleanly without deposit of carbon in the cylinder and without waste carbon in the exhaust.

In order to start the engine it is only necessary to supply oil and water to the charge chamber and to turn the engine over so as to compress air in the compression chamber or cylinder. The relatively high compression usually to 300 pounds to the square inch, 100 which, theoretically, should produce a temperature of not less than 400 degrees C, acting on the thin walls of the charge chamber is sufficient to bring the oil in the chamber to approximately this temperature and I find 105 that ignition takes place under these conditions with certainty.

The cup shaped disk 21 perforated as described aids in spreading or scattering the oil or oil and steam discharged from the 110 charge chamber.

For the purpose of supplying additional oxygen to maintain the combustion of the ignited gases in the helical chamber 19 an air inlet duct 22 controlled by a suitable check 120 valve may be formed through the portion 5 of the charge forming and igniting device.

I do not herein claim the apparatus shown and described, said apparatus forming the subject-matter of a separate application filed 125 by me on the 2nd day of February 1920, Serial No. 355,540.

Having thus described my invention what I claim is;

1. The method of forming an explosive 130

- charge for an internal combustion engine which consists in introducing oil into a confined space, compressing air in the engine, heating the oil in the confined space, 5 opening the confined space to release the oil into the combustion space of the engine and simultaneously introducing water into the confined space and converting it into steam at high pressure by contact with the heated 10 oil to cause it to expel the oil and scatter it in finely divided particles through the air compressed in the combustion space so as to form an explosive mixture therewith.
2. The method of forming an explosive 15 charge for an internal combustion engine which consists in introducing oil into a confined space, heating air by compressing it in the engine, causing the air so heated to heat the oil in the confined space, opening 20 the confined space to release the oil into the combustion space of the engine and simultaneously introducing water into the confined space and converting it into steam at high pressure by contact with the heated 25 oil to cause it to expel the oil and scatter it in finely divided particles through the air compressed in the combustion space so as to form an explosive mixture therewith.
3. The method of forming an explosive 30 charge for an internal combustion engine which consists in introducing oil into a confined space, compressing air in the engine, heating the oil in the confined space, opening the confined space to release the 35 oil into the combustion space of the engine and simultaneously introducing water at normal pressure into the confined space and converting it into steam at high pressure by contact with the already heated oil to cause 40 it to expel the oil and scatter it in finely divided particles through the air compressed in the combustion space so as to form an explosive mixture therewith.
4. The method of forming an explosive 45 charge for an internal combustion engine which consists in introducing oil into a confined space, heating air by compressing it in the engine, causing the air so heated to heat the oil in the confined space, opening 50 the confined space to release the oil into the combustion space of the engine and simultaneously introducing water at normal pressure into the confined space and converting it into steam at high pressure by contact 55 with the already heated oil to cause it to expel the oil and scatter it in finely divided particles through the air compressed in the combustion space so as to form an explosive mixture therewith.
- 60 5. The method of forming an explosive charge for an internal combustion engine
- which consists in introducing oil into a confined space, compressing air in the engine, heating the oil in the confined space, opening the confined space to release the oil into the combustion space of the engine and simultaneously introducing water into the confined space into contact with the already heated oil, the heat of the oil being such as to instantly convert the water into steam at 65 such pressure as to produce an explosive effect and to cause it to expel the oil and scatter it in finely divided particles through the air compressed in the combustion space with such force as to cause ignition of the 70 explosive mixture formed.
6. The method of forming an explosive charge for an internal combustion engine which consists in introducing oil into a confined space, heating air by compressing it in the engine, causing the air so heated to 75 heat the oil in the confined space, opening the confined space to release the oil into the combustion space of the engine and simultaneously introducing water into the 80 confined space into contact with the already heated oil, the heat of the oil being such as to instantly convert the water into steam at such pressure as to produce an explosive effect and to cause it to expel the oil and scatter it in finely divided particles through the air compressed in the combustion space with such force as to cause ignition of the 85 explosive mixture formed.
7. The method of forming successive explosive charges in an internal combustion engine which consists in introducing oil into a confined space to form an initial charge, heating air by compressing it in the engine, causing the air so heated to heat the 90 oil in the confined space, opening the confined space to release the oil into the combustion space of the engine and simultaneously introducing water into the confined space into contact with the already 95 heated oil, the heat of the oil being such as to instantly convert the water into steam at such pressure as to produce an explosive effect and to cause it to expel the oil and scatter it in finely divided particles through the air compressed in the combustion space with such force as to cause ignition of the 100 explosive mixture formed.
